UNITED STATES PATENT OFFICE.

RUSSELL B. KINGMAN, OF ORANGE, NEW JERSEY, ASSIGNOR TO USEFUL PRODUCTS COMPANY, OF WEST ORANGE, NEW JERSEY, A CORPORATION OF NEW JERSEY.

MEMORY-CHECKING DEVICE.

Application filed May 20, 1927. Serial No. 192,842.

This invention relates to improvements in memory checking devices commonly called kitchen reminders, and of the general kind and character illustrated and described in 5 my previously issued Letters Patent of the United States, granted December 21, 1926, No. 1,611,645.

The present invention has for its principal object to provide a novel construction of 10 movable marker or indicator in combination with a novel arrangement of elements for mounting the same on the panel or board of the device. The novel arrangement of marker mounting means being such that the 15 marker is yieldably held immovable against accidental displacement in either active or inactive position, and especially to the end that accidental displacement of the markers from desired position by jars, draughts of 20 air, or other uncontrolled causes is prevented.

Other objects of this invention, not at this time more particularly enumerated, will be clearly understood from the following detailed description of the same.

The invention is clearly illustrated in the accompanying drawings, in which:

Figure 1 is a face view of the novel reminder device made according to and embodying the principles of the present invention; Figure 2 is an edge elevation or side view of the same; Figure 3 is an enlarged detail cross sectional view, taken on line 3-3 in Figure 1; Figure 4 is a fragmentary 35 perspective of a marker mounting and retaining means; and Figure 5 is a perspective view of a marker detached device.

Similar characters of reference are employed in all of the hereinabove described 40 views, to indicate corresponding parts.

Referring now to said drawings, the reference character 1 indicates a tablet body made of sheet metal, and provided, if desired, with a peripheral flange 2, whereby said tablet body is stiffened against distortion. Suitably inscribed upon the face of said tablet body are lists of the names of articles subject to checking or indication, said lists preferably comprising a column of items adjacent to the left hand margin of the tablet body and a similar column of items adjacent to the right hand margin thereof. Arranged in a novel manner for pivotal connection with the tablet body, along the vertical mar-

ginal portions thereof to correspond to the 55 items of the respective columns, are indicating devices or markers capable of being moved or turned from a normal non-indicating or non-checking position to an active indicating or checking position, and vice 60 versa.

Each indicating device comprises a pointer member 3, preferably in the form of an arrow-head; said pointer-member having at 65 its rearward end a shank-portion 4 provided at its extremity with oppositely and laterally projecting flat journal tongues or lugs 5. Preferably each pointer-member 3 is treated on one face with a color corresponding to the color of the tablet body 1; the pointer-member being so mounted that the so colored faces are exposed when the same occupy non-indicating or non-checking positions. The opposite face of each pointer-member is treated with a color adapted to offer a substantial contrast to the color of the tablet body 1; the latter faces being exposed when the pointer-members are turned to occupy 70 indicating or checking positions.

The novel means for pivotally connecting 80 the pointer-members to the tablet body 1, and whereby the same are yieldably held immovable in either active or inactive positions relative to the items listed on the tablet body, is comprised in the following structure. The tablet body is provided adjacent to each item of the lists with a longitudinally extending depressed seat 6 formed in the metallic material of the same. Struck upwardly out of the metallic material of said 85 tablet body, or otherwise suitably formed and connected therewith, are pairs of longitudinally spaced transversely extending spring fingers or tongues 7, which are preferably upwardly arched or bowed into arcuate 90 shape, and so positioned as to extend over the depressed seats 6; one end of each finger or tongue is free for movement and the opposite end is fixed, whereby the fingers or tongues are upwardly yieldable.

The pointer-members 3 are assembled with the tablet body by inserting the flat journal tongues or lugs 5 thereof beneath the spring fingers or tongues 7, so that the former lie in the depressed seats 6, with the shanks 4 105 disposed intermediate and parallel to the spring fingers or tongues 7, while said flat journal tongues or lugs underlie the spring

fingers. When the parts are thus assembled, the spring fingers tensionally bear downward upon the flat journal lugs 5 of the pointer members when the same are either in active or inactive position, thus holding the same yieldably immovable against accidental displacement from either such position, while nevertheless capable of being manipulated to turn the same to either one position or the other as may be desired. When manipulating the pointer-members to selectively dispose the same in either active or inactive position, the spring fingers 7 will yield to the rotation of the flat journal lugs 5, as indicated in Figure 3 of the drawings. The depressed seats 6 will hold the pointer members against displacement from operative relation to the tablet body, when the same are turned, since such seats provide bearings for the pivotal or turning movements of the journal lugs, and the spring fingers 7 serve as keepers to retain the latter in such bearings. A further advantage of the arrangement for thus pivotally connecting the pointer members with the tablet body lies in the fact, that the assembling operations are very simple it being required merely to slip the journal lugs beneath the spring fingers and into the depressed seats, no special tools being required nor especially skilled labor necessary.

In order to retain the free ends of the pointer members 3 spaced outwardly from the surface of the tablet body, when said members occupy either active or inactive positions, and thus disposed so as to be easily accessible by the fingers of the user when it is desired to turn the same from one position to the other, I provide in connection with said pointer members 3 spacing stops to engage the surface of the tablet body. To such end the rearward point at one side of the arrow-head like body of each pointer member is bent downwardly to form a spacing stop 8 which is adapted to engage the surface of the tablet body when the pointer occupies its active indicating position; and the rearward point at the opposite side of the arrow-head like body of each pointer member is bent upwardly or in an opposite direction, so that when the latter is turned over into inactive non-indicating position a spacing stop 9 is formed and provided the same being adapted to engage in like manner the surface of the tablet body to hold the free end of the pointer member outwardly spaced from the tablet body when occupying said latter position, all of which will be

clearly evident from an inspection of the drawings.

As indicated in Figure 3 the pointer members 3 are selectively manipulatable to move the same to checking or indicating positions relative to the items of the lists with which they are associated; and due to the novel construction and arrangement establishing their movable relation to the tablet body, said pointer members are not easily subject to accidental displacement from any given or selected position to which they may have been moved in the use of the device.

Having thus described the present invention, I claim:—

1. In a memory checking device, a metallic body plate having inscribed on its face groups of itemized information, pointer members adjacent to and corresponding to the respective items, said pointer-members having arrow-shaped heads and rearwardly extending shanks terminating in laterally and oppositely extending flat journal lugs, said body plate having depressed seats to receive said journal lugs, and arcuate spring fingers struck up from said body-plate to overlie and retain said journal lugs in said seats and to yieldably engage the flat faces of the same to retain said pointer members normally immovable in either active or inactive position.

2. In a memory checking device, a metallic body plate having inscribed on its face groups of itemized information, pointer members adjacent to and corresponding to the respective items, said pointer-members having arrow-shaped heads and rearwardly extending shanks terminating in laterally and oppositely extending flat journal lugs, said body plate having depressed seats to receive said journal lugs, arcuate spring fingers struck up from said body-plate to overlie and retain said journal lugs in said seats and to yieldably engage the flat faces of the same to retain said pointer members normally immovable in either active or inactive position, the lateral projections of the head of each pointer-member being respectively bent in opposite directions out of the plane of the latter to provide body plate engaging stops whereby the same are spaced from the surface of said body plate when occupying either active or inactive positions.

In testimony, that I claim the invention set forth above I have hereunto set my hand this 19th day of May, 1927.

RUSSELL B. KINGMAN.
